UNITED STATES PATENT OFFICE.

FRANK NOLTE, OF EASTON, MINNESOTA.

GRINDING-MILL.

937,950.

Specification of Letters Patent. Patented Oct. 26, 1909.

Application filed May 10, 1909. Serial No. 494,996.

To all whom it may concern:

Be it known that I, FRANK NOLTE, a citizen of the United States, residing at Easton, in the county of Faribault and State of Minnesota, have invented certain new and useful Improvements in Grinding-Mills, of which the following is a specification.

This invention relates to grinding mills for grinding grain feed and the like, and has for its object to provide certain improvements with respect to the grinding burs as well as with respect to the parts for supporting the same, as will more fully appear from the following description and the accompanying drawings.

In the drawings,—Figure 1 is a central vertical sectional elevation of the mill. Figs. 2 and 3 are top and bottom views of the upper or fixed bur. Fig. 4 is a top view of the bottom or moving bur. Fig. 5 is a detail in top view of the arched frame. Fig. 6 is a detail in plan of the lower frame and sills.

Referring specifically to the drawings, 1 is an arched iron frame which is cast in one piece and which has a bearing for the vertical driving shaft 3. This frame is braced at the back by a brace 16 bolted to the frame 1 at the top and to the wooden frame or sills 2 at the bottom. This brace gives rigidity 30 and strength to the frame.

4 is a cylinder having internal spiral ribs, and this is bolted to the lower frame 15 which has three arms bolted at their outer ends to the frame 2. Within the cylinder 4, 35 and upon the shaft 3 is a screw 5, with a spiral in reverse to that of the cylinder, and which acts to partly disintegrate the feed or material and to force the same down to the burs at the bottom of the cylinder.

40 The upper stationary bur is indicated at 6, and is shown in detail in Figs. 2 and 3. It is corrugated on the under side, and has segmental openings 6^a through which the material is fed. The lower or running bur 45 7 is mounted upon a squared part 9 of the shaft 3, and this bur acts in coöperation with the bur 6, the contacting faces of the burs being corrugated to effect the grinding action. The lower bur 7 is mounted upon or 50 supported by a lazy bur 8, the bur 7 having lugs 7^a on the under side which fit in notches in the top of the lazy bur. The squared part

9 of the main shaft fits in a socket in the top of the lazy bur, and said bur 8 has a depending journal 8^a which extends through 55 a hole in the bottom of the box 17 and rests in a step bearing 10. This step bearing is formed in a cross bar 10^a which is supported at one end by a bolt 13 depending from the frame 15 and having an adjusting nut 13^a, 60 and at the other end by a bolt 11 which extends through the frame 15 and has a spring 11^a coiled around the same. The purpose of this spring is to allow the burs to yield or spring apart in the event that a piece 65 of iron or other hard material should get in between the burs. The discharge box 17 is bolted to the under side of the frame 15 and has an outlet chute 14 in the side thereof.

20 are wings cast on the lazy bur 8 and 70 turning therewith in the box 7, and these wings act to force the ground material out through the discharge 14.

The cylinder 4 is flanged at the bottom where it rests on the frame 15, and confines 75 the upper bur 6 the edge of which is flanged to rest in a rabbet around the central opening in the frame 15, and the cylinder and box are preferably secured to the frame by the same bolts. The shaft 3 is provided at the 80 top with a driving pulley 13.

The mill can be readily taken apart by dropping the bar 10^a and removing the box 17, allowing the lazy and lower burs to fall off the shaft. This allows the running bur 85 to be readily changed whenever desired. The provision of the spring support for the lower bur prevents injury to the burs in the event of metal, rock, or other hard material being fed between the same, and after such 90 material passes out the spring returns the burs to original position. The pressure of the burs may also be varied by adjusting the wing nut 13^a, or the nut which confines the spring. 95

I claim:

In a grinding mill, in combination, a cylinder having internal spiral ribs, a shaft extending through the cylinder and having a grinding screw coöperating with said ribs, 100 a stationary bur through which the shaft extends, and forming a bottom for said cylinder and provided with openings to permit passage of the material from the cylinder

through the bur, a running bur loose and non-rotatable on the shaft under said stationary bur, a casing inclosing the burs, and a rotary supporting member having a bearing in the top for the lower end of the shaft and inclosed within the casing, and also having a depending journal extending through the bottom of the casing, and a supporting bear-

ing for said journal, under the bottom of the casing.

In testimony whereof, I affix my signature in presence of two witnesses.

FRANK NOLTE.
